UNITED STATES PATENT OFFICE.

OTTO FRIELING, OF ESSEN, GERMANY, ASSIGNOR TO FRIED. KRUPP AKTIENGESELLSCHAFT, OF ESSEN-ON-THE-RUHR, GERMANY.

APPARATUS APPLICABLE TO RAILWAY-GUNS FOR TRANSFERRING AMMUNITION FROM AN AMMUNITION-WAGON.

1,363,862.

Specification of Letters Patent. Patented Dec. 28, 1920.

Application filed September 8, 1920. Serial No. 408,972.

To all whom it may concern:

Be it known that I, OTTO FRIELING, residing at Essen, Germany, a citizen of the German Republic, have invented a certain new and useful Improvement in Apparatus Applicable to Railway-Guns for Transferring Ammunition from an Ammunition-Wagon, of which the following is a specification.

10 This invention relates to an apparatus for transferring ammunition from an ammunition wagon to railway guns.

The invention will be described with reference to the accompanying drawings:—

15 Figure 1 shows diagrammatically a side elevation of one form of the apparatus together with those parts of a gun carriage which are concerned and also of an ammunition wagon in the position occupied when 20 transferring ammunition.

Fig. 2 is a plan view of Fig. 1 and

Fig. 3 is a side elevation of the apparatus and of those parts of a gun carriage and ammunition wagon which are concerned, in 25 the position occupied when traveling.

Fig. 4 is a view corresponding to Fig. 1 of a modified form of the invention.

Figs. 5 and 6 are views corresponding to Figs. 1 and 2 of a further modified form of 30 the invention.

Figs. 7 and 8 show in side and rear elevation a detail drawn to a larger scale of the form of the invention shown in Figs. 5 and 6.

35 Referring to the arrangement shown in Figs. 1 to 3 of the drawings the railway gun carriage is provided with a frame A which carries the gun and is supported on two sets of bogies. The rear set of bogies

40 A¹ (Figs. 1 and 3) can be locked relatively to the frame A both in the traveling position and in a special firing position. In the traveling position (see Fig. 3) the set of bogies A¹ is brought up close to the front

45 set of bogies (not shown in the drawing) so that the gun does not project out laterally too far on curves and consequently the contour of the railway is well utilized. In the firing position the set of bogies A¹ is pushed

50 so far to the rear that the gun barrel when fired at any elevation and recoiling on the firing of the shot does not strike against the set of bogies.

To the set of bogies A¹ is attached a

frame B which is provided with a track b¹ 55 for an ammunition tray C. The frame B carries on the end next to the frame A of the gun carriage two vertical axes of rotation b² (see Figs. 1 and 3) for two jib arms b³, which are swung about the axis b² into a 60 loading position or can be retracted into a traveling position. In the loading position the arms b³ bridge over the gap between the frame B and the frame of the gun carriage. They then form an extension of the 65 track b¹ of the frame and join on to a track a² (see Figs. 1 and 2) mounted on the frame A of the gun carriage. In the rear end of the frame B are arranged two jib arms b⁵ 70 adapted to be swung about vertical axes b⁴ (Figs. 1 and 2) and which when in the loading position project freely over the frame of an ammunition wagon D coupled to the set of bogies A¹. The arms b⁵ form in this position a track for an auxiliary wagon E 75 (see Figs. 1 and 2). A crane F is also mounted on the frame B.

When transferring ammunition the ammunition wagon D is coupled to the set of bogies A¹. The set of bogies is locked relatively to the gun carriage frame A in its rear position (the firing position) and the arms b³ and b⁵ of the frame B are swung into the loading position. In the ammunition wagon, the ammunition, a projectile for 85 example, is lifted by means of a block and tackle or the like on to the auxiliary carriage E and this latter run on to the arms b⁵ and underneath the crane F. The projectile G is then raised by the crane F and, after 90 the auxiliary carriage has been pushed back and the tray C has been run under the crane, is then lowered on to the tray C. The tray C is then brought on the track b¹ b³ a² and up to the breech end of the gun barrel. 95 Prior to the firing of the shot the ammunition wagon D is uncoupled from the set of bogies A¹ and run back. By this means blows against the ammunition wagon are avoided when the railway carriage runs back 100 after the firing of the gun.

If the gun is to be brought into the traveling position the ammunition wagon D is again coupled to the set of bogies A¹, after which the auxiliary carriage E is lifted off 105 the arms b⁵ and set down on the carriage D. The arms b⁵ and likewise the arms b³ are folded back against the frame B and finally

the set of bogies A¹ is pushed forward and locked relatively to the gun carriage frame A in its traveling position. This movement of the set of bogies is possible because by 5 folding back the arms b³ the gap between the rear end of the gun carriage frame and the frame B is opened.

The arrangement described above is distinguished by the fact that the transferring 10 device owing to its connection with the set of bogies and on account of its short length which it possesses after the jib arms have been swung inward on their axes, does not project too far laterally on curves. It is 15 also advantageous that the arms b⁵ are not supported on the ammunition wagon D in the loading position, so that no adjustment is required when the frame of the ammunition wagon rises owing to the reduction 20 of weight on the springs which takes place as the wagon is emptied.

In the form shown in Fig. 4 of the drawings the track b¹ of the frame B is inclined and the swinging jib arms b³ b⁵ are so constructed that they form in the loading position together with the track b¹, a track for the ammunition tray C, which rises from the ammunition wagon to the gun carriage frame A. The tray C is drawn up this track 25 by means of a rope (H). The auxiliary carriage E and the crane F described above with reference to the first arrangement will not be required in this construction of the apparatus.

35 In the arrangement shown in Figs. 5 to 8 the only substantial difference between it and that shown in Figs. 1 to 3 is that both the jibs b⁶ which act as a track for the auxiliary carriage E and also the jibs b⁷ on which 40 the ammunition tray C runs when loading, are longitudinally movable with respect to the loading frame B. The jibs b⁶ have a smaller gage than the track b¹ of the frame B, so that they can be pushed between the 45 rails of this track and the jibs b⁷, to which rails b⁸ are fixed for the tray C to run on are mounted on trucks b⁹ (see particularly Figs. 7 and 8) upon which they can be 50 swung about horizontal axes b¹⁰ lying in the longitudinal direction of the rails b⁸. In the loading position the jibs b⁷ are turned 55 inward about the axes b¹⁰ (see the position shown by full lines in Fig. 7), so that the rails b⁸ lie in line with and form an extension of the track b¹ to the rails a² provided on the gun carriage frame A. If the jibs are to be moved out of operation they are 60 turned back in an outward direction into the position shown by dot and dash lines in Fig. 7 in which position the jibs b⁷ with their rails b⁸ lie laterally of the track b¹ and therefore can be pushed along it. The adjustment of the rails b⁸ into their two positions might be effected by moving the

65 rails at right angles to the longitudinal direction instead of swinging them into position about horizontal axes.

Claims:

1. The combination with a railway gun carriage comprising a body having a set of 70 bogies longitudinally adjustable relatively thereto, provided with a loading frame, an ammunition tray and a track therefor.

2. An apparatus of the class described 75 which comprises in combination with a railway gun carriage comprising a body having a set of bogies longitudinally adjustable relatively thereto, a loading frame mounted on said movable set of bogies, a track supported on the loading frame, an ammunition tray and movable extensions for said 80 track at both ends of the loading frame.

3. An apparatus of the class described 85 which comprises a railway gun carriage comprising a body having a set of bogies longitudinally adjustable relatively thereto, an ammunition tray mounted on said set of bogies, a track supported on said loading frame for said tray and displaceable track extensions carried by said loading frame, 90 as and for the purpose set forth.

4. An apparatus of the class described 95 which comprises a railway gun carriage comprising a body having a set of bogies longitudinally adjustable relatively thereto, a loading frame carried by said set of bogies, an ammunition tray, a track on said loading frame for said ammunition tray and swinging track extensions carried by 100 said loading frame.

5. An apparatus of the class described 105 which comprises the combination with a railway gun carriage comprising a body having a set of bogies longitudinally adjustable relatively thereto, a loading frame carried by said movable set of bogies, an ammunition tray and a track therefor carried by 110 said loading frame and displaceable track extensions projecting from each end of the loading frame and enabling said ammunition tray to travel from an ammunition wagon to a track on the gun frame.

6. An apparatus of the class described 115 which comprises a railway gun carriage comprising a body having a set of bogies longitudinally adjustable relatively thereto, a loading frame carried by said set of bogies, a track on said frame, an ammunition tray adapted to run on said track, and longitudinally movable track extensions carried by 120 said frame.

The foregoing specification signed at Es-
sen, Germany, this 27th day of May, 1920.

OTTO FRIELING.

In presence of—

HANS GOTSMANN,
JOSEF OLCERTZ.
